UNITED STATES PATENT OFFICE

CLAUDE M. DIBBLE, OF JOLIET, ILLINOIS, ASSIGNOR TO MOORE BROTHERS COMPANY,
OF JOLIET, ILLINOIS, A CORPORATION OF ILLINOIS

DESIGN FOR A ROOM HEATER

Application filed September 27, 1930. Serial No. 37,077. Term of patent 7 years.

To all whom it may concern:

Be it known that I, CLAUDE M. DIBBLE, a citizen of the United States, residing at Joliet, county of Will, and State of Illinois, have invented a new, original, and ornamental Design for a Room Heater, of which the following is a specification, reference being had to the accompanying drawing, forming a part thereof:

The drawing is a perspective view of the heater embodying the design of the present invention.

The drawing illustrates a perspective view of the heater from the front and one side, and it will be understood that the two sides are alike in appearance and that the design does not extend to or include the appearance of the rear of the heater.

I claim:

The ornamental design for a room heater as shown and described.

CLAUDE M. DIBBLE.
